US0D1098955S

(12) **United States Design Patent** (10) Patent No.: **US D1,098,955 S**
(45) Date of Patent: ** *Oct. 21, 2025

(54) **HYDROPONIC PLANT CONDUIT ASSEMBLY**

(71) Applicant: **BL United, LLC**, North Little Rock, AR (US)

(72) Inventor: **Luis Campos**, North Little Rock, AR (US)

(73) Assignee: **BL United, LLC**, North Little Rock, AR (US)

(*) Notice: This patent is subject to a terminal disclaimer.

(**) Term: **15 Years**

(21) Appl. No.: **29/857,321**

(22) Filed: **Oct. 20, 2022**

(57) **CLAIM**

The ornamental design for a hydroponic plant conduit assembly, as shown and described.

DESCRIPTION

FIG. 1 is a perspective exploded view of a hydroponic plant conduit assembly, showing my new design;

FIG. 2 is a bottom plan view of FIG. 1;

FIG. 3 is a top plan view of FIG. 1;

FIG. 4 is a right side elevation view of FIG. 1;

FIG. 5 is a left side elevation view of FIG. 1; and,

FIG. 6 is a front elevation view of FIG. 1.

1 Claim, 3 Drawing Sheets
